Primary Examiner — Lauren D McVey

(57) **CLAIM**

The ornamental design for a monitor arm, as shown and described.

DESCRIPTION

FIG. 1 is a top, rear and left side perspective view of a monitor arm showing our new design;

FIG. 2 is a bottom, front and right side perspective view thereof;

FIG. 3 is a rear elevational view thereof;

FIG. 4 is a front elevational view thereof;

FIG. 5 is a right side view thereof;

FIG. 6 is a left side view thereof;

FIG. 7 is a top plan view thereof;

FIG. 8 is a bottom plan view thereof; and,

FIG. 9 is a bottom, front and right side perspective view showing the monitor arm in a state of use.

The broken lines in FIGS. 1-8 illustrate portions of the monitor arm that form no part of the claimed design.

The broken lines in FIG. 9 illustrate portions of the monitor arm and environmental subject matters that form no part of the claimed design.

1 Claim, 9 Drawing Sheets
